UNITED STATES PATENT OFFICE.

JOHN RUSSELL, JR., OF ROSEMOUNT, MINNESOTA.

DRAG-SAW.

SPECIFICATION forming part of Letters Patent No. 267,721, dated November 21, 1882.

Application filed June 30, 1882. (No model.)

To all whom it may concern:

Be it known that I, JOHN RUSSELL, Jr., a citizen of the United States, residing at Rosemount, in the county of Dakota and State of Minnesota, have invented certain new and useful Improvements in Sawing-Machines, of which the following is a specification.

This invention relates to machines for sawing logs into proper lengths for timber, shingles, fire-wood, &c., after the trees have been felled; and it consists in the construction and arrangement of parts, as hereinafter shown and specifically claimed.

In the drawings, Figure 1 is a perspective view of the machine complete. Fig. 2 is a plan view, and Fig. 3 is a side view of the adjusting mechanism of the combined log-holding brace and guide detached. Fig. 4 is a plan view detached of the treadles. Figs. 5, 6, 7, 20 and 8 are enlarged detached detail views of the lever-couplings and chain-segments, illustrating their construction. Figs. 9 and 10 are outline diagrams of the different parts of the machine, showing their relative positions at two parts of the stroke of the saw.

A is a base piece or plate, having a seat, B, at one end and pivoted at the other end at *a* in two straps, C' C². These straps curve upward and backward at *c*, and run back parallel 30 with the base A, and are bent downward each side of the base and connected to a standard, D, by bolts or other suitable fastenings.

E is a foot or brace having a lateral slot, *d*, through one end and "spurs" *e* in the lower 35 end, and with the upper end resting between the curved portions *c* of the straps C' C², as shown.

g' is a bolt passing through the strap C' C², and also through the slot *d*, so that the brace 40 E may be moved endwise the length of the slot and still be held between the straps. By tightening up the bolt *g'* the brace may be "pinched" between the straps and prevented from being moved from side to side.

Upon top of the brace E, between the curved 45 parts *c*, an inclined plate, F, having teeth *h*, is bolted, said teeth adapted to engage with a bolt, *g²*, passing through the straps C' C² at the upper part of the curved portions *c*, as shown 50 in Figs. 1, 2, and 3. By this means the relative angles between the brace E and base A and standard D may be altered to any extent

by loosening the bolts *g'* *g²*, and setting the teeth *h* upward or downward over the bolt *g²*, and then tightening the bolts again to prevent 55 side play.

The spurs *e* are intended to be set into the log G, which is being sawed, and by the adjustability of the brace E the straps C' C² and standard D may be retained in the same position no matter how large or small the log may be, as hereinafter more fully shown.

H is the main saw-operating lever, passing down through a slot, K, in the base A, and provided with a handle, *i'*, in the upper end, and pivoted to the saw I at the lower end. The handle *i'* is made adjustable higher or lower by the holes *i²* to adapt it to the person operating the saw. Upon either side of this lever H, near its center, two plates, L' L², are bolted, having hubs *m'* *m²* 70 upon their sides, through which a shaft, M, passes and is keyed fast therein. Projecting from the front of these plates, about opposite the shaft M, are two ears, L³ L⁴, having a series of holes, *n'*, between which the upper end 75 of a connecting-rod, N, is held by a bolt, *n²*, while the lower end is held by a bolt, *n³*, in the slot K of the base A.

P' P² are two collars, loose upon the shaft M, just outside the hubs *m'* *m²* of the plates L' L², 80 and provided with downwardly-projecting ears P³ P⁴, to which the straps C' C² are bolted, as shown more clearly in Figs. 5, 6, and 7, by which arrangement the lever H is pivoted to the straps C' C².

Outside the collars P' P² and straps C' C², upon the ends of the shaft M, are keyed two segmental grooved sheaves, R' R², having hooks *t'* *t²*, adapted to receive the ends of chains R³ R⁴, which pass over said segmental sheaves 90 and down to two foot levers or treadles, T' T², to which they are secured by hooks *u'* *u²*. The upper ends of these treadles are pivoted by a hanger, T³, near the lower end of the base A, and connected to each other by a cross-piece, 95 T⁴. (See Fig. 4.) This cross-piece T⁴ is provided with a number of holes, so that the lower ends of the treadles may be set nearer together or farther apart to adapt their foot-plates or stirrups T⁵ T⁶ to the feet of the operator. By 100 shortening or lengthening the chains R³ R⁴ the heights of the treadles may also be adapted to the operator. The seat B is made adjustable along the base A for the same purpose,

and still another adjustment may be obtained by means of the holes n' in the ears $L^3 L^4$. By these several adjustments the machine may be perfectly adapted to the size of the operator 5 and to his weight.

The brace E has a slit, v , in its lower part, in which the saw I runs, the brace thus serving the triple purpose of a brace for the log being acted upon, a foot or support for the frame of 10 the saw operating mechanism, and a guide for the saw.

In using the saw the operator mounts the seat B with one foot upon each of the stirrups $T^5 T^6$, and grasps the handles i' , (the brace 15 E and saw I having first been properly adjusted and set.) He then pulls the lever H toward him, and at the same time presses downward with his feet upon the treadles $T' T^2$. This action throws the saw I forward, and by 20 means of the chains $R^3 R^4$ and segments $R' R^2$ the shaft M is revolved and the lever H assisted in its work. By these movements the operator lifts himself up from the seat B , so that the raising of the base A by the rod N , 25 which will occur when the lever H is drawn backward, will not be counteracted by the weight of the operator, and then, when the lever H is pushed backward at the return-stroke of the saw, the weight of the operator 30 will assist the action by pulling down upon the ears $L^3 L^4$ through the rod N and revolving the shaft backward in the collars $P' P^2$. During the return-stroke of course the feet of the

operator must not press upon the treadles 35 $T' T^2$.

The relative positions of the parts are shown by the outline diagrams of Figs. 9 and 10, Fig. 9 showing the position when the forward stroke is about one-third completed, and Fig. 10 showing the position at the completion of 40 the forward stroke. The saw may thus be made to travel very close to the ground when the cutting is completed, no matter what size the log may be, as the lower end of the lever H may be kept at the same distance from the 45 ground at the lowest point of its stroke by adjusting the brace E .

What I claim as new is—

1. The standard D , straps $C' C^2$, having the saw-operating lever H , pivoted therein, and provided with curved ends c and bolts $g' g^2$, in combination with the brace E , having the toothed plate F , slot d , and slit v , and spurs e , substantially as and for the purpose specified. 50
2. The straps $C' C^2$, a supporting standard, D , and a saw-brace, E , in combination with a base, A , hinged at one end to straps $C' C^2$, a saw-operating lever, H , pivoted between straps $C' C^2$, and having a hinged connection with base A , foot-treadles $T' T^2$, having a hinged 60 connection with base A , and suspended by elevating-chains, substantially as and for the purpose set forth.
